(57) **CLAIM**

The ornamental design for a complementary support for a cradle that holds an electronic device, as shown and described.

DESCRIPTION

FIG. 1 is a front perspective view of a complementary support for a cradle that holds an electronic device;

FIG. 2 is a rear perspective view thereof;

FIG. 3 is a front view thereof;

FIG. 4 is a rear view thereof;

FIG. 5 is a top view thereof;

FIG. 6 is a bottom view thereof;

FIG. 7 is a left side view thereof; and,

FIG. 8 is a right side view thereof.

The broken lines depict environmental structure, and are included for illustrative purposes only and form no part of the claimed design.
